UNITED STATES PATENT OFFICE

114,593

DESIGN FOR A SUCTION CLEANER

Ward Leathers, Haworth, N. J., assignor to Quadrex Corporation, New York, N. Y.

Application August 5, 1938, Serial No. 79,125

Term of patent 14 years

To all whom it may concern:

Be it known that I, Ward Leathers, a citizen of the United States, residing at Haworth, in the county of Bergen and State of New Jersey, have invented a new, original, and ornamental Design for a Suction Cleaner, of which the following is a specification, reference being had to the accompanying drawing, forming a part thereof.

In the drawing:

Fig. 1 is a side elevation of the suction cleaner showing my new design; and

Fig. 2 is a top plan view of the same.

My design for a suction cleaner comprises essentially four zones; a pan-like bottom portion for use as a dirt-receptacle, a filtering zone thereabove, a motor-blower-unit zone above said filtering zone, and a top zone with a carrying handle.

I claim:

The ornamental design for a suction cleaner, substantially as shown and described.

WARD LEATHERS.
